UNITED STATES PATENT OFFICE.

FRED E. ASELTINE, OF DAYTON, OHIO, ASSIGNOR TO GENERAL MOTORS RESEARCH CORPORATION, OF DETROIT, MICHIGAN, A CORPORATION OF DELAWARE.

CHARGE-FORMING DEVICE FOR INTERNAL-COMBUSTION ENGINES.

Application filed September 5, 1925. Serial No. 54,592.

This invention relates to charge-forming devices for internal combustion engines, especially such engines as are used for propelling automobiles.

5 The general object of the invention is to provide a device which will deliver equal quantities of fuel charge of the same mixture ratio to each cylinder of a multicylinder engine under the various conditions of load and 10 engine speed to which the engine may be subjected. This invention provides various improvements over the disclosure in my prior application, Serial No. 4,665, filed January 26, 1925.

15 A special object of this invention is to provide an improved liquid dash pot for stabilizing and modifying the action of the suction-actuated main air inlet valve.

Another object is to provide an improved 20 engine accelerating device, whereby a richer fuel mixture is momentarily obtained upon the sudden opening of the manually operated throttles.

Another object is to provide an improved 25 fuel-distributing means, having a plurality of individual primary carburetors each supplying an overrich fuel mixture to a separate branch of the air manifold leading to an engine intake port.

30 Another object is to provide an automatically-actuated, passage-restricting means on the engine side of the manually-operated throttle, whereby the entering fuel charge is delivered to the engine intake ports at 35 high velocity, thereby preventing the deposition of liquid fuel particles on the passage walls.

Another object is to provide a compact, rugged structure for carrying out the above 40 objects.

Further objects and advantages of the present invention will be apparent from the following description, reference being had to the accompanying drawings, wherein a 45 preferred form of the present invention is clearly shown.

In the drawings:

Fig. 1 is a plan view of a charge-forming device for a six-cylinder internal combustion engine, built according to this invention.

Fig. 2 is a section on line 2—2 of Fig. 1 and shows the relation of one branch of the intake pipe to the engine intake valve of an L-head 55 engine.

Fig. 3 is a side elevation of the device shown in Fig. 1 and shows the manually actuated arm for changing the spring tension on the spring closed main air inlet valve.

Fig. 4 is a vertical section on the broken line 4—4 of Fig. 1 and shows in particular the liquid fuel ducts leading from the float bowl to the two distributing canals for the primary carburetors.

Fig. 5 is a vertical section on the broken line 5—5—5 of Fig. 1.

Fig. 6 is a section through one of the primary carburetors and is taken on the line 6—6 of Figs. 1 and 8.

Fig. 7 is a plan view of the central part of the device with the distributing block containing the primary carburetors removed, and shows in dot and dash lines the position of the distributing canals contained in said 75 distributing block.

Fig. 8 is an enlarged plan view of the distributing block containing the distributing canals for the three primary carburetors shown in dotted lines therein.

Fig. 9 is a bottom view of the distributing block.

Similar reference characters refer to similar parts throughout the several views of the drawings.

Numerical 10 designates in its entirety the air manifold provided with the three branches 11, 12 and 13, each of which branches connects to an engine intake port, which serves two adjacent cylinders. Since it is well known in both four and six cylinder engines to provide only one engine intake port to serve two adjacent cylinders, such engine construction is not shown in detail in the drawings. Fig. 2 shows only one engine intake valve 15 of the 95 pair of similar intake valves served by the branched intake passage 14 and intake port 16 in the cylinder block casting. The air manifold casting 10 has a main air inlet opening 17 which is covered by the air inlet fitting 18 having the main air inlet 19 and the intake valve 20. Located directly under the inlet valve 20 is the fuel float chamber 30 which is provided with the annular float 31 and float-operated fuel inlet valve 32 for maintaining 100 constant fuel level in chamber 30. Liquid fuel from a suitable supply tank is led to the valve 32 through the pipe connection 33, hollow screw 34 and duct 35, all as clearly shown in Fig. 5. This duct 35 and its related parts are 110

105

110

preferably carried in a casting 36 which is separate from the manifold casting 10, but which is held in rigid relation therewith by the internesting circular flanges 37 and 38, 5 and the two clamping bolts 40 which extend through suitable ears on the castings 10 and 36. These clamping bolts 40 also extend through suitable ears on the air inlet fitting 18 and the float bowl 30, and thus clamp all 10 these parts rigidly together, as clearly shown in Fig. 3.

The main air inlet valve 20 has a valve stem 50 extending down through the guide 51 in casting 36 and is provided at its lower end 15 with a dash pot piston 52 which cooperates with the dash pot cylinder 53 located within the fuel bowl 30 and surrounded by the annular float 31 therein. The piston 52 has one or more holes 54 therein (two being shown in 20 Fig. 4) and a loose disk check valve 55 for closing the holes 54 upon downward movement of the piston as will be clear from Fig. 4. The dash pot cylinder 53 remains filled with 25 liquid fuel at all times the fuel entering through suitable holes 56 above the piston 52 but below the fuel level 57 in float bowl 30. The wall of the dash pot cylinder 53 is provided with a by-pass duct 58 of about $\frac{1}{8}$ -inch diameter, which freely by-passes liquid around 30 piston 52 after the valve 20 has moved down a predetermined amount to uncover the by-pass port 59 (see Fig. 5). The air valve 20 is urged to its seat by the coil spring 60 whose upper end engages the spring seat disc 61 35 held against a shoulder on the valve stem 50, and whose lower end engages the vertically-adjustable spring cup 62 which slides within guide cylinder 63 in casting 36. The cup 62 is adjusted up or down by means of a yoke 64 rigidly secured to a transverse shaft 65 having 40 suitable bearings in the casting 36. The two arms of the yoke 64 have slotted extremities 66 engaging diametrically-opposite pins 67 on the cup 62. These pins 67 project 45 through and ride in the slots 68 in the walls of the guide cylinder 63 (see Fig. 5). The transverse shaft 65 is actuated by lever arm 69 secured to the projecting end of shaft 65. The tension of spring 60 may be adjusted at 50 will by the operator by suitable manually-actuated linkage attached to lever 69 and extending to the driver's seat. The minimum or normal tension on spring 60 is adjusted by the screw 70 which limits the downward 55 movement of cup 62, as will be clear from viewing Fig. 3. The air valve 20 is opened according to the depression in the air manifold 10, its opening movement being damped by the leakage of fuel past the dash pot piston 52, the check valve 55 being closed. During 60 its initial opening movement the damping effect is at a maximum, but as the valve 20 opens more and more, the damping effect of the dash pot progressively reduces due to the 65 leakage through by-pass port 59 becoming

greater and greater as the top edge of the piston 52 approaches the port 59. After piston 52 fully uncovers port 59, the damping effect is greatly reduced due to the $\frac{1}{8}$ -inch diameter by-pass 58. The air valve 20 is permitted to 70 close quite rapidly by the opening of check valve 55 in piston 52 during the upward motion of said piston.

It will be noted that a thin plate 75 is provided to insure that equal parts of the air entering the air inlet horn 19 will flow through the three outlet branches of the manifold. This plate is secured between the air inlet horn and the top of the manifold immediately above the middle outlet branch of said 80 manifold permitting a flow past the air controlling valve directly into this manifold branch. The purpose of this plate should be obvious. The resistance to flow through the end branches of the manifold is greater than 85 that through the middle branch because of the greater distance through which the air has to flow, and if air were permitted to flow directly into said middle branch the volume of air flowing to the engine through said middle 90 branch would be greater than that flowing through the end branches. The plate 75 operates as a baffle around which the air flowing through the middle outlet branch of the manifold must pass, making the resistance to flow 95 through, and the volume of charge supplied by, the various branches equal.

The primary carburetors for supplying an overrich fuel mixture to each of the branches 11, 12 and 13 of the air manifold will now be 100 described. The casting 36 has an upstanding portion 80 extending upwardly alongside the central branch 12 of the air manifold 10. This portion 80 contains the two vertical fuel ducts 81 and 82, which branch in parallel 105 relation from the fuel duct 83. Duct 83 is extended to a point below the fuel level 57 by the long metering plug 84 which has the fuel-metering orifice 85 therein. The portion 80 terminates at the top in a flat table 86 having 110 two screw-ears 87 thereon (see Fig. 7). The distributing block, designated as a whole by numeral 90, has a corresponding flat surface 91 (see Fig. 9), which is rigidly secured upon the table 86 by the two screws 92 which are threaded into the ears 87. The flat surface 91 of the distributing block 90 is provided with two separate fuel-distributing canals 93 and 94 which register with the vertical fuel ducts 81 and 82, respectively, as 115 shown by the dot and dash lines in Fig. 7. The distributing block 90 contains three parallel bores 95, 96 and 97, of the same diameter, each of which bores extends above and across the fuel-distributing canals 93 and 94 120 adjacent the open end of each of said bores (see Figs. 8 and 6). The fuel canal 93 admits fuel to each of the bores 95, 96 and 97 through a high-speed fuel jet 98, and the canal 94 admits fuel to each of said bores by a low- 125

speed fuel jet 99, thus forming three individually-metering primary carburetors 100, 101, and 102. Primary air enters each of these carburetors through an air-metering bushing 105 which projects into the bores 95, 96 and 97 past both fuel jets 98 and 99 (see Fig. 6). The fuel jets 98 and 99, therefore, deliver fuel to the annular space 106 between the bushing 105 and the walls of the corresponding bore, and hence the entering air does not impinge directly upon the fuel jets. Any variation in the flow of fuel through these jets due to turbulence in the entering air stream is thus avoided and hence more accurate and uniform metering of the liquid fuel is obtained. The vertical fuel duct 81 contains a gravity metering valve 88 whose tapered end cooperates with the valve seat 89. During idling or low engine speeds this valve 88 rests upon its seat 89 and hence fuel is supplied to the primary carburetors 100, 101 and 102 only through canal 94 and the low-speed jets 99. As the engine speed is increased by opening the manually-actuated throttles, the suction on the primary carburetors is increased sufficiently to cause the liquid fuel to lift valve 88 from its seat and thus permit fuel to also flow through the high-speed jets 98 in the primary carburetors. The valve 88 is lifted more and more, according to the increase in engine speed and hence acts as a variable restriction or metering orifice for the high-speed jets 98. The weight of the valve 88 is made such that it remains upon its seat at engine speeds below about 400 R. P. M. or a car speed of about 10 miles per hour. At this speed valve 88 begins to pass a small amount of fuel to the high-speed jets 98 and as the speed increases from this point on the jets 98 supply a progressively increasing amount of fuel to the primary carburetors. Of course, the relative sizes of the various jets and orifices and the weight of valve 88 must be so chosen that the primary carburetors function properly, as described above. The following weights and sizes have been found to give good results with a six cylinder 36 H. P. automobile engine: weight of valve 88, 3½ grams; diameter of valve seat 89, $\frac{3}{16}$ of an inch; size of each of jets 98, No. 60 drill; size of each of jets 99, No. 73 drill; size of fuel orifice 85 supplying total fuel for all three primary carburetors, No. 53 drill; size of each of primary air orifices 105, No. 35 drill.

The overrich air-and-fuel mixture from the primary carburetors 100, 101 and 102 is led directly into the throat portion of a relatively large venturi 110 in each of the branches 11, 12 and 13 of the air manifold. The bore 95 of the distributor block 90 leads directly to the hole 111 in the central branch 12, the distributor block being rigidly anchored to branch 12 by the screw 112. The bore 96 leads through a small pipe 113, of about the

same diameter as said bore, to the pipe fitting 114, which is rigidly secured to the branch 13 by the screw 115, so that the duct 113 registers with the hole 111 which leads down into the throat of the venturi 110 in the branch 13. Each of the venturis 110 is held tightly up against a shoulder 116 in each branch by a tapered set screw 117 which rides against a cam surface 118 on the venturi (see Fig. 2). Preferably the floor 120 of the air manifold 10 is raised to lie approximately on a level with the bottom 121 of the throat of venturi 110. This prevents the puddling of liquid fuel on the floor 120 ahead of the venturi 110 at low throttle openings and enables the entering air stream to more easily sweep all liquid fuel which may be deposited upon the floor of the venturi into the branch 13 and thence into the engine cylinder. The small amount of liquid fuel which may accumulate in the small crescent-shaped depression 122 at low throttle positions will have no deleterious effect. However, this depression 122 may be avoided simply by filling with metal, that is, by designing the venturi 110 so that its bottom portion completely fills the depression 122 and lies flush with the floor 120.

A throttle valve 125 is located in each of the branches 11, 12 and 13 immediately behind the venturi 110 to control the fuel charge entering each engine intake port 16. Each throttle 125 is mounted upon a separate rotatable shaft 126 having bearings in suitable bosses 127 integral with the respective branches. The three shafts 126 are all interconnected by the two shafts 128 which are connected to the projecting ends of the shafts 126 by means of the universal joints 130. The universal joints 130 each comprise a two-armed spider 131 rigidly secured to one end of shaft 128, and a similar two-armed spider 132 adjustably secured to one end of a throttle shaft 126 by the clamping screw 133. The two spiders 131 and 132 are rigidly riveted to a thin annular ring 135 of flexible metal by means of the rivets 134. It will be clear that these universal joints 130 not only render the exact alignment of throttle shafts 126 unnecessary, but also that they will permit relative longitudinal movement between the two coupled shafts and hence will eliminate any possible binding of the accurately fitted throttle valves 125, due to unequal expansion of the manifold 10 and the shafts 128 and 126. Each throttle 125 may be rotatably adjusted relative to the universal coupling 130 by loosening the screw 133 and turning shaft 126 within the boss of spider 132. By this means the throttles 125 may be accurately adjusted after assembly, so they will all close exactly together. One of the universal coupling members 132, preferably one attached to the central throttle shaft 126, is provided with a depending lever arm 136 by which means all the throttles 125 are concurrently manually

actuated. Suitable mechanical linkage (not shown) connects the lever arm 136 to an ordinary hand throttle lever or foot accelerator, located in convenient reach of the driver. 5 The lever arm 136 is also provided with the usual idle-position-adjusting screw 137 which engages the stop lug 138. These parts are shown only in plan in Fig. 1, but it is thought the construction will be clear when taken 10 with the above description.

In order to increase the velocity of the fuel mixture as it enters each of the engine intake ports 16, an automatic passage-restricting means is provided in each of the branches 11, 15 12 and 13 (see Fig. 2). This means comprises a thin-walled inner tube 140, of slightly less diameter than the inside diameter of the branch 13, which is held rigidly in place 20 against the top wall of the branch by the screw 141 and two or more lugs 142 which are preferably tongues, cut out of the metal of tube 140 and turned down at suitable angles to form legs for spacing the tube 140 from the bottom of branch 13. Within the tube 25 140 are mounted two flapper valves 143 which pivot upon the centrally-mounted shaft 144. The valves 143 are urged to closed position by the small coil tension springs 145 which are suitably fastened at one end to the valves 30 143 and at the other end to the eyes 146 in the spring support 147 which, preferably, is also pivoted upon the shaft 144 in central slots in the valves 143. The springs 145 are made sufficiently strong to hold valves 143 closed when 35 the throttle 125 is in its nearly closed positions and thus compel all the entering charge to pass through the restricted crescent-shaped passage 148 between the tube 140 and the walls of branch 13. The velocity of the entering 40 charge is thereby greatly increased and passes up to the engine intake valve 15 at high speed, thus carrying all the unvaporized fuel particles therein into the engine cylinder and preventing any deposition or accumulation of 45 liquid fuel upon the floor or walls of the engine intake passage 14. Preferably the tube 140 extends a short distance within the passage 14, as clearly shown in Fig. 2, in order to carry the restriction in the intake passage 50 beyond the engine ports 16, so that the entering charge will be given less chance to slow down materially before entering the valve 15. As the throttle valve 125 is opened to admit a greater charge to the engine, the springs 145 55 will yield according to the entering blast upon the flapper valves 143 and permit the valves 143 to open to a position to pass this greater charge at a sufficiently high velocity to prevent deposition of liquid fuel in the passage 60 14. When the entering charge has reached a maximum value, that is, when the throttle 125 is full open and the engine is running at high speed, the two valves 143 will be fully open and hence permit the practically unrestricted 65 passage of the charge to the cylinder. The relative location of the spring eyes 146 and the shaft 144 is such that the springs 145 have their tension increased at a less and less rate as the valves 143 open wider and wider. The effect of this feature is to cause a relative 70 greater restricting tendency for small incoming charges than for large incoming charges. For large charges no restriction by the valves 143 is needed to prevent deposition of liquid fuel in intake passage 14 and hence the resisting force of springs 145 on valves 143 when in full-open position is made only large enough to properly initiate the closing movement of the valves upon the next reduction in the amount of incoming charge. Thus 75 any tendency of the valves 143 to reduce the volumetric efficiency of the engine at full throttle is practically overcome.

A depression-equalizer tube 150 interconnects all the branches 11, 12 and 13 at a point 80 between the throttle 125 and the engine cylinders. At low-opening throttle positions this tube 150 causes a substantially-constant equal depression on the engine side of the throttles in all the branches 11, 12 and 13, and 85 hence causes each of the six engine cylinders to draw in equal charges. The method of functioning of this equalizer tube is described in greater detail in my above-mentioned copending application, Serial No. 90 4665.

A résumé of the operation of the device so far described is as follows: With the engine idling, the throttles 125 are in nearly-closed position, hence there is a large depression on the engine side of the throttles 125, but only a relatively small depression in the air manifold 10. This small depression is transmitted through the holes 111 in venturis 110 and the pipes 113 to the primary carburetors 100, 101 and 102, causing primary air to enter through bushings 105 and fuel to enter through low-speed jets 99, forming a rich mixture to be delivered to each venturi 110 through holes 100 111. At such times only a very small amount 105 of air enters the manifold 10 through the spring-closed air valve 20 since the depression in air manifold 10 is small, and hence the rich mixture entering the branches through the holes 111 is not over-diluted with 110 air from the main air inlet 19. Now, when it is desired to increase the engine speed, the throttles 125 are opened wider, which, of course, increases the depression in manifold 10. This increased depression is transmitted 115 back to the primary carburetors and causes them to deliver a still richer mixture to the branches through the holes 111 due to the functioning of the second fuel jets 98. This increased depression in manifold 10 also opens the air valve 20 further and admits a greater 120 amount of air to properly dilute the rich fuel mixture through holes 111, thus maintaining the proper ratio of air and fuel going to the engine. The dash pot 52, 53 prevents possible 125 130

qua fluttering of the air valve 20 due to pulsations 10 of the engine suction, especially at low engine speeds, and also damps the opening of air valve 20 in order to cause the increased 15 depression in manifold 10 to act first on the primary carburetors upon the opening movement of the throttles 125. The dash pot by-pass 58 progressively reduces this damping effect upon air valve 20 as the throttles 125 20 reach their more fully-open position with the engine running at high speed, since under these conditions this damping effect is not so much desired. If at any time it is desired 25 to increase the richness of the mixture, for instance when starting the engine, the operator actuates the lever 69 to increase the compression on spring 60. This, of course, permits less air to enter valve 20 than otherwise 30 would under the then conditions and hence permits the primary carburetors to deliver a richer mixture to the engine cylinders. Preferably the operating linkage for lever 69 is arranged to hold it in any position to which the operator may move it, thus permitting the operator to run the engine for any desired 35 period of time on an enriched mixture. It is pointed out that the lever 69 does not act simply as an ordinary choking arrangement since the valve 20 is still permitted to open 40 according to the depression in manifold 10 and thus function to control the mixture ratio under varying conditions. It acts to enrichen the mixture throughout all the said varying conditions.

35 An accelerating device for momentarily enriching the charge upon a sudden opening of the throttles 125 will now be described.

A fuel chamber 160 is rigidly secured below the float bowl 30 by means of the threaded 40 plug 161 which is screwed into the bottom of the dash pot cylinder 53. A passage 162 in plug 161 forms communication between the chamber 160 and the dash pot cylinder 53 below the piston 54. A flexible metal bellows 163 is sealed to the bottom of chamber 160 and a coil spring 164 therein serves to urge the wall 165 of bellows 163 upwardly into contact with the plug 161, as shown in Fig. 4. The interior of bellows 163 communicates through passage 166 in the pipe connecting plug 167 with a small duct 168 which leads to the engine intake above the throttles 125. This duct 168 preferably branches from the equalizing tube 150 at some convenient point, 55 and thereby maintains a uniform depression in bellows 163 equal to the average depression in all three of the branches 11, 12 and 13 above the throttles. At all low opening throttle positions, this depression in bellows 163 collapses said bellows until the wall 165 thereof engages the adjustable stop pin 170 which is threaded into the plug 167 and provided with a lock nut 171 for holding the pin 170 in adjusted position. When bellows 60 65 163 is collapsed, fuel is drawn through pas-

sage 162 to fill the chamber 160 around about said bellows. Now when the throttles 125 are suddenly opened by the driver to accelerate the car the depression in equalizer tube 150 and hence in bellows 163 is suddenly reduced, thereby permitting spring 164 to expand the bellows, thus pumping fuel from chamber 160 into the dash pot 53. Obviously this action opposes the opening movement of the main air valve 20 momentarily and thus causes a richer mixture to be delivered to the engine to give a more powerful accelerating charge. The exact amount of fuel pumped into the dash pot 53 to give the proper accelerating effect may be accurately adjusted by the vertical adjustment of the stop pin 170, as clearly illustrated in Fig. 4. The strength of bellows spring 164 is preferably so chosen that the bellows 163 will not be collapsed by the depression therein when the throttles 125 are in their more open positions, for instance, at one-quarter open and above. Therefore further sudden opening of the throttles from such positions will not be accompanied by an increased resistance to the opening of air valve 20 due to a pumping action of bellows 163. Such cutting out of the accelerating device at the larger throttle openings is usually desired since, ordinarily, at the higher engine speeds there is a temporary starving of the engine under a sudden increase in the throttle opening.

While the form of embodiment of the invention as herein disclosed constitutes a preferred form, it is to be understood that other forms might be adopted, all coming within the scope of the claims which follow.

What is claimed is as follows:

1. In a charge forming device for a multi-cylinder internal combustion engine having a plurality of intake ports, an air manifold having a branch leading to each of said intake ports and a common main air inlet, a spring closed valve in said main air inlet opened by the depression in said manifold, and a constant level fuel chamber located below said valve and containing a liquid dash pot for controlling the movement of said air inlet valve, and individual primary carburetors for supplying an overrich fuel mixture to each of said branches, said primary carburetors being all supplied from said fuel chamber.

2. In a charge forming device for a multi-cylinder internal combustion engine having a plurality of intake ports, an air manifold having a branch leading to each of said intake ports and a common main air inlet, a spring closed valve in said main air inlet opened by the depression in said manifold, and a constant level fuel chamber located below said valve and containing a liquid dash pot for controlling the movement of said air inlet valve, said dash pot having a liquid by-pass duct in the walls thereof so located

- as to be uncovered by the dash pot piston for reducing the damping effect upon the air valve in its more open positions.
3. In a charge forming device for an internal combustion engine having an intake port, a main air inlet, a spring closed valve in said main air inlet opened by the engine suction, a dash pot for damping both the opening and closing movement of said valve, said dash pot being so arranged that the opening movement of said valve is damped to a greater degree than the closing movement thereof.
4. In a charge forming device for an internal combustion engine having an intake port, a main air inlet, a spring closed valve in said main air inlet opened by the engine suction, a dash pot for damping the opening movement of said air inlet valve, said dash pot having a by-pass duct in the walls thereof for decreasing the damping effect upon said air inlet valve in its more open positions.
5. In a charge forming device for a multi-cylinder internal combustion engine having a plurality of intake ports, an individual primary carburetor having an individual fuel metering jet for supplying a fuel mixture to each intake port, all of said primary carburetors being supplied with fuel from a common source through a common metering orifice.
6. In a charge forming device for a multicylinder internal combustion engine having a plurality of intake ports, an individual primary carburetor for supplying a fuel mixture to each intake port, each primary carburetor having a low speed fuel jet and a high speed fuel jet, and a common fuel flow control means for all of said high speed jets.
7. In a charge forming device for a multi-cylinder internal combustion engine having a plurality of intake ports, an individual primary carburetor for supplying a fuel mixture to each intake port, each primary carburetor having a low speed fuel jet and a high speed fuel jet, and a common automatic fuel metering valve for all of said high speed jets.
8. In a charge forming device for a multi-cylinder internal combustion engine having a plurality of intake ports, an individual primary carburetor for supplying a fuel mixture to each intake port, each primary carburetor having a low speed fuel jet and a high speed fuel jet, and a common gravity actuated fuel flow restricting valve for all of said high speed jets.
9. In a charge forming device for a multi-cylinder internal combustion engine having a plurality of intake ports, an individual primary carburetor for supplying a fuel mixture to each intake ports, each primary carburetor having a low speed fuel jet and a high speed fuel jet, all of said low speed jets taking fuel from a common liquid fuel supply at closely related points, and all of said high speed jets taking fuel from a common liquid fuel supply at closely related points, whereby the pressure conditions in the liquid fuel supply for all the jets of each set is the same.
10. In a multicylinder internal combustion engine having a plurality of intake ports, a pipe for supplying a fuel mixture to each of said ports, a throttle valve in each of said pipes, common means for concurrently actuating all of said throttle valves, and an automatically closed, suction-opened, passage-restricting valve in each of said pipes located on the engine side of said throttles.
11. In a multicylinder internal combustion engine having a plurality of intake ports, a pipe for supplying a fuel mixture to each of said ports, a throttle valve in each of said pipes, common means for concurrently actuating all of said throttle valves, and an automatically closed, suction-opened, passage-restricting valve in each of said pipes located on the engine side of said throttles and relatively close to the engine intake ports.
12. In a charge forming device for an internal combustion engine, a main air inlet, an automatically closed valve in said inlet opened by the engine suction, a dash pot for modifying the movement of said valve, and means actuated upon a sudden increase in the amount of charge drawn into the engine for momentarily increasing the resistance of said dash pot to the opening movement of said air valve, whereby a temporary enriching of the charge is obtained.
13. In a charge forming device for an internal combustion engine, a main air inlet, an automatically closed valve in said inlet opened by the engine suction, a dash pot for modifying the movement of said valve, and means actuated upon a sudden increase in the amount of charge drawn into the engine for pumping fluid into said dash pot and thereby increasing the resistance of said dash pot to the opening movement of said air valve.
14. In a charge forming device for an internal combustion engine, a main air inlet, an automatically closed valve in said inlet opened by the engine suction, a dash pot for modifying the movement of said valve, and a bellows actuated upon a sudden increase in the amount of charge drawn into the engine for pumping fluid into said dash pot and thereby increasing the resistance to the opening movement of said air valve.
15. In a charge forming device for an internal combustion engine, an intake passage, a fuel aspirating means for mixing fuel with the air passing to the engine through said passage, a throttle valve in said passage on the engine side of said aspirat-

- ing means, an automatically closed air valve in said passage on the inlet side of said aspirating means, and suction-operated means actuated upon the opening movement of said 5 throttle for urging said air valve toward closed position.
16. In combination with an internal combustion engine, a charge intake passage, a carburetor, a throttle in said passage on the 10 engine side of said carburetor, an air inlet valve for said carburetor, and suction-operated means actuated upon the opening movement of said throttle for urging said air valve toward closed position.
- 15 17. In a charge forming device for an internal combustion engine, an intake passage, a fuel aspirating means for mixing fuel with the air passing to the engine through said passage, a throttle valve in said passage on the 20 engine side of said aspirating means, an automatically closed air valve in said passage on the inlet side of said aspirating means, and means actuated by the change of depression above the throttle upon the opening 25 movement of said throttle for resisting the opening movement of said air valve.
18. In a charge forming device for an internal combustion engine, a main air duct having a suction controlled air inlet valve 30 and a throttle therein, a fuel supply passage leading into said air duct between said inlet valve and throttle and subject to the suction between said inlet valve and throttle, and an independent suction actuated fuel valve 35 metering the flow of fuel to said fuel supply passage.
19. In a charge forming device for an internal combustion engine, a main air duct having a suction controlled air inlet valve 40 and a throttle therein, a primary carburetor supplying an overrich mixture to said air duct between said inlet valve and throttle, and an independent suction controlled fuel metering valve 88 metering the fuel supply 45 to said primary carburetor.
20. In a charge forming device for an internal combustion engine, a main air duct having a suction controlled air inlet valve and a throttle therein, a primary carburetor supplying an overrich mixture to said air duct 50 between said inlet valve and throttle, said primary carburetor having a low speed fuel jet and a high speed fuel jet, and an independent suction controlled fuel valve 88 controlling the fuel supply through said high speed 55 fuel jet.
21. A charge forming device for internal combustion engines comprising a mixing chamber, a fuel inlet therefor, a fuel chamber
- supplying fuel to said inlet and an air inlet 60 bushing projecting into said mixing chamber, said bushing extending over said fuel inlet and spaced therefrom whereby the incoming air is prevented from passing directly in contact with said fuel inlet. 65
22. A charge forming device for internal combustion engines comprising a mixing chamber, a plurality of fuel inlets admitting fuel to said mixing chamber, a fuel chamber supplying fuel to said inlets, and an air inlet 70 bushing projecting into said mixing chamber to admit air thereto, said bushing extending over both said fuel inlets and spaced therefrom whereby the incoming air is prevented from passing directly in contact with either 75 of said fuel inlets.
23. A charge forming device for internal combustion engines comprising a secondary mixing chamber, a primary carburetor adapted to deliver a mixture of fuel and air to said 80 secondary mixing chamber, said primary carburetor comprising a mixing chamber, a fuel inlet therefor, a fuel chamber supplying fuel to said inlet and an air inlet bushing projecting into said mixing chamber, said bushing 85 extending over said fuel inlet and spaced therefrom whereby the incoming air is prevented from passing directly in contact with said fuel inlet.
24. A charge forming device for internal combustion engines comprising a plurality of secondary mixing chambers one of which is associated with each engine intake port, a plurality of individual primary carburetors, each of which is adapted to deliver a mixture 90 of fuel and air to one of said secondary mixing chambers, each of said primary carburetors comprising a mixing chamber, a fuel inlet therefor, and an air inlet bushing projecting into said mixing chamber, said bushing 95 extending over said fuel inlet and spaced therefrom, whereby the incoming air is prevented from passing directly in contact with said fuel inlet. 100
25. A charge forming device for an internal combustion engine having in combination a mixing chamber a fuel inlet therefor, a main air inlet, a suction operated spring controlled valve therein, means for retarding the opening of said valve on opening of the throttle to enrich the mixture for acceleration, and means for rendering the retarding means ineffective after a predetermined movement of the air valve. 105
- In testimony whereof I hereto affix my signature.

FRED E. ASELTINE.
